UNITED STATES PATENT OFFICE.

LESTER R. WELLMAN, OF CHICAGO, ILLINOIS.

DESIGN FOR A BRACKET BACK FOR LIGHTING FIXTURES.

Application filed November 28, 1924. Serial No. 11,525. Term of patent 3½ years.

To all whom it may concern

Be it known that I, LESTER R. WELLMAN, a citizen of the United States, residing at Chicago, in the county of Cook and State of Illinois, have invented a new, original, and ornamental Design for Bracket Back for Lighting Fixtures, of which the following is a specification, reference being had to the accompanying drawing, forming part thereof.

Figure 1 shows a view in front elevation of a bracket back for lighting fixtures embodying my design and, Figure 2 shows a side elevational view thereof.

I claim:

The ornamental design for a bracket back for lighting fixtures, as shown.

L. R. WELLMAN.
